UNITED STATES PATENT OFFICE.

GRACE DE LA PARELLE, OF EAGLE ROCK, CALIFORNIA.

MUSICAL INSTRUCTION BLOCKS.

Application filed June 27, 1921. Serial No. 480,740.

To all whom it may concern:

Be it known that I, GRACE DE LA PARELLE, a citizen of the United States, residing at Eagle Rock, Los Angeles County, California, have invented a certain new and useful Improvement in Musical Instruction Blocks, of which the following is a full, clear, and exact description, such as will enable others skilled in the art to which it applies to make and use the same, reference being had to the accompanying drawings, forming part of this specification.

My invention relates generally to new and useful improvements in musical instruction devices and more particularly to a relatively simple and practical apparatus, including a set of blocks or cards that are adapted to be assembled upon a suitable holder for the purpose of imparting to persons making use of the device, a certain degree of knowledge relating to music, its arrangement and characters.

The principal objects of my invention are to provide a relatively simple musical instruction device, that may be easily and cheaply produced and which, in addition to affording instruction to beginners in music, will serve as a novel, interesting and instructive pastime for children and particularly those who are in any degree interested in music.

With the foregoing and other objects in view, my invention consists in certain novel features of construction and arrangement of parts that will be hereinafter more fully described and claimed and illustrated in the accompanying drawings in which:

Fig. 1 is a plan view of a musical instruction device of my improved construction.

Fig. 2 is a longitudinal section taken on the line 2—2 of Fig. 1.

Fig. 3 is an enlarged cross section taken on the line 3—3 of Fig. 1 and showing the device in position upon the music ledge of a piano.

Fig. 4 is a perspective view of one of the musical character bearing blocks forming a part of the device.

Fig. 5 is a perspective view of a printed card or strip that forms a part of the device.

Referring by numerals to the accompanying drawings which illustrate a practical embodiment of my invention, 10 and 11 designate the parts of a shallow pan or holder, said parts being connected to each

other by means of headed rivets 12 seated in the side walls of one member and passing through longitudinal slots 13 that are formed in the corresponding walls of the 60 opposite member. Such arrangement enables the holder to be adjusted in length so as to correspond to the length of the passage of music that is formed by the character bearing blocks that are positioned 65 within said holder. The shape of the holder is such that it may readily be positioned upon the music ledge of a piano or organ as illustrated in Fig. 3.

The character bearing blocks 14 contemplated by my invention are preferably rectangular in form and they may be composed of wood, cardboard, celluloid, metal, earthenware or any desired material.

The blocks are preferably uniform in size, 75 and appearing on the face of each block is a series of five transversely disposed parallel lines 15 that are intended to represent the lines of a musical staff. Thus when a series of the blocks are arranged side by 80 side within the holder, the lines 15 cooperate to produce an extended staff. Appearing on the face of each block and at the proper point on the staff lines 15 thereon, is a musical character such as a note, rest, 85 flat, sharp and the like.

In order to enable the users of the device to set the musical notes to the words of a song, elongated strips 16 of wood, cardboard, metal or the like, are provided on 90 their faces with the words of a song said words and the syllables thereof being arranged in spaces of equal width which are equal to the width of the blocks 14. Thus when a word bearing strip 16 is arranged 95 lengthwise in the lower portion of the holder and a series of the character bearing blocks are positioned above said strip, the notes and characters appearing on said blocks will be disposed directly above the 100 words and the syllables thereof, with the result that the person making use of the device will, in a practical manner, gain knowledge of musical characters, their meaning and their relative positions with respect to 105 each other and with respect to the words of a song. Thus it will be seen that I have provided a relatively simple and practical device which may be easily and cheaply produced and which when used or manipulated 110 will provide a novel, interesting and instructive pastime:

It will be readily understood that minor changes in the size, form and construction of the various parts of my improved musical instruction blocks may be made without departing from the spirit of my invention, the scope of which is set forth in the appended claim.

I claim as my invention:

In a musical instruction device, an elongated strip bearing the words of a song, the syllables thereof being spaced equal dis-

tances along said strip; and a series of relatively narrow musical character bearing blocks of uniform width, corresponding to the spacing of the syllables, which blocks are adapted to be positioned along one edge of said word bearing strip, with one block positioned above each of the syllables of the words printed on said elongated strip. 15

Signed at Los Angeles, California, this 20
7th day of June, 1921.

GRACE DE LA PARELLE.
